WOOD HEEL MACHINE

James S. O'Callaghan, Saugus, Mass.

Application December 10, 1934, Serial No. 756,755

17 Claims. (Cl. 12—42)

This invention relates to a machine for holding and operating upon heels of the type used in ladies' high heel shoes.

These high heels have various curved and rounded surfaces which make them difficult to position accurately and hold for the final operations. The present invention contemplates mechanism for firmly and accurately supporting wood heels while they are acted upon by one or more tools, and contemplates means whereby the heels may be easily and quickly positioned to be operated on by the tools.

One important feature of the present invention resides in a table or support upon which the top surface of a heel may rest for sliding movement, and in a pair of substantially parallel jaws or strips mounted on said support in position to tightly receive the heel between them and the support to thereby firmly hold the heel in an inverted position while it is slid along the jaws or strips into positions to be acted upon by one or more tools.

Another feature of the invention resides in a power actuated plunger for sliding the heel along the support between said strips whereby the heel is introduced between the strips at one end thereof and discharged from the other end of the strips.

A further feature resides in the construction of the jaws or strips whereby one overlies and rests upon a shoulder at the front of the heel and the other engages the sloping rear surface of the inverted heel.

Still a further feature resides in means whereby the different tools are operated in timed relation with the power actuated plunger to cause these tools to perform their functions as the heel is advanced to one or more predetermined positions.

Other features of the invention and novel combination of parts in addition to the above will be hereinafter described in connection with the accompanying drawings which illustrate one good practical form of the invention.

In the drawings:

Fig. 1 is a front elevation of a machine constructed in accordance with the present invention.

Fig. 2 is a rear elevation of the machine of Fig. 1.

Fig. 3 is a transverse sectional view through a portion of the machine of Fig. 1 showing the time shaft.

Fig. 4 on an enlarged scale is an end view of the heel supporting mechanism of the machine of Fig. 1.

Fig. 5 is a top plan view of Fig. 4.

Fig. 6 is a transverse sectional view through the machine of Fig. 1.

Fig. 7 is a longitudinal sectional view taken on the line 7—7 of Fig. 6.

Fig. 8 is a side elevation of a dowel feeding device.

Fig. 9 is a longitudinal sectional view through the device of Fig. 8.

Fig. 10 is a bottom view of mechanism to be described for supporting the dowel driver.

Fig. 11 is a vertical sectional view taken on the line 11—11 of Fig. 1, and

Fig. 12 is a perspective view of the dowel feed trough provided in the hopper of Fig. 11.

In the embodiment of the invention illustrated in the drawings the operating parts of the machine are supported by a suitable frame consisting of the side plates or castings 10 which are secured in spaced relation to each other by the transverse braces 11 and this frame is provided with a table top or supporting surface 12. To the discharge end of the supporting frame just described is secured by bolts or otherwise the angle plate 13 which supports drill press mechanism to be described.

In accordance with the present invention the shoe heel H, upon which certain operations are to be performed, is placed upon the table or supporting surface 12 in an inverted position so that the top surface of the heel rests upon this flat surface as will be apparent from Fig. 4. The high heels of women's shoes usually have a shoulder s at the front of the heel and a curved inclined rear surface, as will be apparent in Fig. 4, and in accordance with the present invention this shoulder s is utilized in holding the heel firmly in place upon the surface 12 while it is acted upon by one or more tools. In the construction shown the heel is snugly but slidably received between the substantially parallel jaws or strips 14 and 15 which are supported in spaced relation to the top of the table 12. The jaw 14 is provided with a rounded edge as shown and is adapted to overlie and grippingly engage the shoulder s. The gripping action of this jaw may be varied by tightening the bolts 16 which extend through holes in the jaw 14 and engage the table 12. In order to secure a slight yielding action between the jaw 14 and shoulder s this jaw is yieldingly supported in spaced relation to the table top by the blade springs 17 which may be clamped to the jaw and table top by the bolts shown.

The slope or curvature of the rear surface of heels may vary with variations in the styles of

the heels. Means is therefore provided whereby the jaw 15 may be adjusted angularly to cause its heel engaging surface to conform to the inclination of the inverted heel H and to this end 5 in the construction shown the jaw 15 is provided with the laterally projecting ears 18 which are pivotally secured by the clamping bolts 19 to a slide or plate 20 mounted upon the table top 12 for adjustment transversely of the table towards 10 and from the jaw 14 to firmly grip the heels between these jaws. The jaw supporting plate 20 may be secured to the table top by the bolts 21 extending through elongated slots 22 in the plate 20 and after the proper adjustment has been 15 secured these bolts may be tightened to firmly secure the plate 20 in place. The transverse movement of the plate 20 is preferably guided by the key 23 secured to the table top. Adjustment of the plate 20 towards and from the heel 20 gripping position may be secured by operating the adjusting screw 24 which is journaled in a bracket 25 secured to the table top and this screw has threaded engagement with the plate 20. The adjusting screw may be rotated by 25 means of the hand knob 26. As will be apparent in Fig. 5 the jaw 14 is preferably somewhat longer than the jaw 15 to facilitate the placing of the heels H at the entrance between the jaws so that when the power operated plunger, to be 30 described, moves forward it will slide the heel along the table top between the substantially parallel jaws. The entrance end of the jaw 15 may be rounded slightly if desired but this is not essential since the curvature of the heel will 35 serve to guide the heel into the space between the jaws.

In the construction shown the heel when placed upon the table top 12 in an inverted position is forced lengthwise of the relatively long 40 jaws by the reciprocating plunger 27 which is slidably supported by the bearing blocks 28 secured to the table top. The forward end of this plunger is preferably provided with a socket, as will be apparent from Fig. 2, adapted to adjustably receive the shank of the heel engaging 45 member 29. The arrangement is such that this heel engaging member may be adjusted longitudinally of the plunger slightly and clamped in the desired position of adjustment by tightening the set bolt 30 threaded in a projection upon the 50 forward end of the plunger. This adjustment of the heel engaging member 29 is provided to vary the distance the heel will be moved lengthwise of the jaws by the forward movement of 55 the plunger 27.

In the construction shown forward movement is imparted to the plunger 27 by a rocking lever 31, the lower end of which is pivotally supported 60 within the machine casing at 32 and the upper end of this lever extends through a slot formed in the plunger 27 as indicated at 33. Forward movement is imparted to the lever 31 by a cam 34 keyed or otherwise rigidly secured to a transverse shaft 35 which will hereinafter be referred 65 to as the time shaft. This shaft, as will be apparent from Fig. 3, is journaled in bosses 36 provided upon the side walls 10 of the supporting frame. The shaft may be held from moving 70 longitudinally in its bearing by the driving sprocket 37 secured at one end of this shaft and by a collar 38 secured to the other end of this shaft. The cam 34 engages a roller 39 pivotally secured to the lever 31 and forces this lever forward to impart a working stroke to the plunger 75

27. This lever in the construction shown is retracted to return the plunger to the dotted line position of Fig. 2 by the spring 40 one end of which may be connected to the lever 31 and the other to the machine frame. 5

The time shaft 35 which is shown as disposed near the forward end of the machine is driven, in the construction shown, from a transverse shaft 41 disposed near the discharge end of the machine, and which will hereinafter be referred 10 to as the clutch shaft. This clutch shaft has loosely journaled thereupon at the rear of the frame 10, a driving sprocket 42 which is driven from a motor 43 by the chain 44. Co-operating with the sprocket 42 is a clutch or disk 45 which 15 is connected to the shaft 41 for sliding movement thereupon into and out of friction engagement with the outer face of the sprocket 42 and the sliding movement of this clutch element 45 into and out of friction engagement with the 20 sprocket 42 is controlled by the lever 46, the upper end of which is pivotally secured to a supporting bracket 47 secured to the casing and the lower end of this lever is operatively connected to the upwardly extending portion 48 of a foot 25 treadle 49. An intermediate portion of the lever 46 has the enlarged hub 50 which is operatively connected to the clutch member 45. The treadle is pivotally supported at 51 upon a bracket 52 secured to the machine casing and the upwardly 30 extending portion 48 of the foot treadle has an elongated slot adapted to receive a pin 53 secured to the lower portion of the clutch operating lever 46. The clutch is normally held in its inactive position by a spring 54 and is held in 35 friction engagement with the sprocket 42 to drive the shaft 41 by depressing the foot treadle 49.

The time shaft 35 is driven from the clutch shaft 41 at a reduced speed by providing a small 40 sprocket 56 upon the shaft 41 adapted to drive a large sprocket 37 upon the shaft 35 by means of a sprocket chain 57 to thereby turn the plunger operating cam 34 in the direction indicated by the arrow in Fig. 2. 45

The mechanism so far described serves to operate the plunger 27 to force a heel H along the table top from the position indicated by I in which it has been placed by hand at the entrance to the jaws 14 and 15 to a position indicated by II near 50 the discharge end of these jaws, as shown in Fig. 5. This will serve to accurately position the heel H in the position II to be drilled and stamped as will be hereinafter described. Whereupon the heel will be moved forwardly between the jaws 55 by the next incoming heel to the position indicated by III, as shown in Fig. 5, in which position a heel strengthening dowel d may be driven into the drill hole formed in the heel while this heel was in the previous position indicated by II. 60

It is desirable to stamp heels during their process of manufacture with numbers or other marks indicating size and style and this is accomplished in accordance with the present invention by providing means for stamping the top surface of the 65 inverted heel while it is in the position II of Fig. 5. To accomplish this in the construction shown the heel stamping dies 58 are positioned below the table top to pass upwardly through a hole 59 in the top of the table to engage the surface of the 70 heel to be stamped. These dies are secured to an operating lever 60, one end of which is pivotally supported at 61 upon lugs or the like 62 extending downwardly from the table top 12 within the 75

machine frame. Operating movement is imparted to this lever 60 by the cam 63 which engages a roller 64 rotatably mounted at the under side of the lever between the spaced ears 65 adapted to straddle the peripheral portion of the cam 63. The lever 60 normally rests in its lower or inactive position in which it is shown in Fig. 7 and is periodically raised by the cam 63 to stamp the heel H.

It is important to apply ink to the stamping dies 58 and this is accomplished in the construction shown by providing the inking roll 66 which is normally supported by the bracket 67 in the inactive position in which this roll is shown in Fig. 7. The inking roll 66 is caused to periodically wipe across the upper ends of the dies 58 by mounting this roll between the horizontally extending links 68 which are pivotally secured at 69 to the upstanding operating levers 70, the lower ends of which levers are pivotally secured at 71 to a transverse brace 11. Rocking movement is periodically imparted to the levers 70 from the lever 31 by the connecting link 72, and a spring 73 serves to force the inking roll 66 downwardly so that it will yieldingly wipe across the upper ends of the stamping dies.

As the heel H is advanced by the plunger 27 from the position in which it is indicated by I in Fig. 5 towards the position indicated by II it is acted upon by a rotating circular saw 14 which cuts off the end of the heel to shape this end to receive the usual top lift. The saw 14 in the construction shown is driven by the motor 15 which is supported for movement in a substantially vertical direction towards and from the table top and also for angular adjustment, to thereby vary the height of the shoe heel and the angle at which the surface shall be cut to receive the top lift. The motor 15 is supported, in the construction shown, for the adjustments just mentioned by an angle plate 16 to the upright portion of which is pivotally mounted at 17 the angularly adjustable plate 18, and this plate is clamped in the desired position of angular adjustment by tightening the angle clamp 19.

The motor 15 is provided with a supporting head 80 mounted upon the angularly adjusted plate 18 for sliding movement and adapted to be adjusted towards and from the work by rotating the crank handle 81 to turn the motor adjusting screw 82. The circular saw 14 is shown as having the usual guards 83.

As soon as a heel H has been advanced by the plunger 27 to the position indicated by II in Fig. 5 it may be acted upon by the twist drill 84 which may be supported and operated by the drilling mechanism 85 supported upon the angle plate 13. This drill press has the driving motor 86 which by means of the belt 87 drives a drill operating spindle which is rotatably mounted in the hollow shaft 88 which is non-rotatably but slidably supported by the frame of the drill press. The entire drill press is mounted upon the angle plate 13 at an inclination to the vertical to accommodate the angle at which the heel is to be drilled and the drill 84 is normally held in its raised position by the spring 89. This drill is periodically lowered to drill the heel, in the construction shown, by providing upon the clutch shaft 41 the drill lowering cam 90 which is adapted to depress the lever 91, one end of which is pivotally supported from the machine frame at 92. To the opposite end of this lever 91 is pivotally connected the link 93, the upper end of which is connected by the bolt 94 to a plate or casting 95 rigidly secured

to the non-rotating drill shaft 88. The connecting link 93 is preferably constructed with overlapping parts which may be clamped in different positions of adjustment by the bolt 96, as best shown in Fig. 2, to vary the overall length of this link and thereby vary the degree to which the drill 84 will be forced downwardly by the operating mechanism just described.

The cams 63 and 90 are not secured to the clutch shaft 41 in the present construction but are rigidly secured to a sleeve 97 journaled upon the shaft 41 and this shaft is driven from the time shaft 35 by the chain 98 which passes around a sprocket 99 upon the time shaft and the sprocket 100 upon the sleeve 97 to drive this sleeve and the cams secured thereto.

In accordance with the present invention means is provided whereby when the drill 84 is lowered to drill a heel H in the position indicated by II a dowel driver will be operated at this time to drive a dowel d in a heel occupying a position indicated by III at this time. This is accomplished by constructing the casting 95 so that it will adjustably support the dowel driving pin 101 positioned to align with a hole in a heel occupying the position indicated by III. In order to secure the proper lateral and longitudinal position of the dowel driving pin 101 the casting 95 is preferably formed as shown in Fig. 10 so that the pin 101 may be rigidly clamped by the bolt 102 in the pin supporting block 103 and this block may be adjusted towards and from the axis of the drill spindle and laterally by adjusting the different bolts 104. These various adjustments will serve to accommodate the distance which may exist between the two heels shown in Fig. 5 when one is being drilled and the dowel is being driven into the other.

In the construction shown the dowels to be driven in the heels are supplied from a hopper 105, which hopper may be supported above the frame of the machine by the upright 106. The dowels are fed from this hopper through the tube 107 which leads from the hopper to the dowel feeding device 108 which is supported by a bracket 109, as best shown in Fig. 6, directly above the heel in which the dowel is to be driven.

It is important that the dowels be supplied to the tube 107, one at a time in a continuous series, and this is secured in the construction shown by providing in the hopper 105 the dowel feeding trough 110. The upper end of this trough, as best shown in Fig. 12, is large enough to receive a stack of several dowels but as they slide down this trough the V-shaped groove thereof decreases in height as indicated by 111 to a size in which it will retain only one dowel and the other dowels will slide down the inclined walls 112 to be returned to the lower portion of the hopper. The single row of dowels that remain in the trough 111 are directed into the feed tube 107.

The dowels are delivered one at a time into the dowel feeding device 108 directly in front of the forward end 113 of the plunger 114 which is slidably mounted in the hollow casing of the dowel feeding device 108. This sliding plunger 114 is periodically operated to advance a dowel from a position directly below the feed tube 107, see Fig. 8, to the dowel driving position 115 and serves to hold the dowel in this position directly above the heel until the driving pin 101 is lowered and drives the dowel into the heel. When the slide 114 is in its lowermost position a dowel sup-

plied by the tube 107 will drop in front of the forward end of this slide and will be yieldingly held in this position by a spring 116, the forward end of which extends through an opening in the 5 side wall of the casing to engage the dowel.

When the slide 114 is advanced from its retracted position of Fig. 8 a dowel entering the casing 108 will then drop upon the shoulder 117 of the slide and will be held in this elevated 10 position until the slide 114 is again retracted under the action of the compression spring 118 which yieldingly urges the slide to its retracted position against the stop 119. The means shown for periodically feeding the slide forward in its 15 casing 108 comprises the flexible cable 120 secured at 121 to the slide and which passes around a pulley 122 and upwardly to the sliding shaft 88 of the drill press so that the upward movement of this shaft will tension the cable 120 and pull the 20 slide 114 forward. A spring 123 is preferably connected to this cable to hold the slide yieldingly at the forward end of its stroke.

The means shown for elevating the dowels in the hopper 105 to supply the trough 110 with 25 these dowels comprises a vertically movable slide 124, the upper end of which is trough-shaped and slopes towards the trough 110 to cause these dowels to slide from the upper end of the slide 124 into the trough 110. Reciprocatory movement is imparted to the slide 124, in the construction shown, by the rod 125, the lower end of which is pivotally secured to the outer end of the transversely extending lever 126, as best shown in Fig. 6. The other end of this lever is pivotally secured 30 at 127 to the supporting lugs 128 and an intermediate portion of this lever rests upon the die operating lever 60. The arrangement is such that each time the lever 60 is forced upwardly by its operating cam it will raise the transversely 35 extending lever 126 to thereby elevate the dowel feeding slide 124.

Having described the various parts of the embodiment of the invention shown, the operation is as follows: When it is desired to operate the 45 machine the motor 43 is started and the treadle 49 is held depressed to engage the clutch 45 and drive the clutch shaft 41. This drives the time shaft 35 through the chain 57 and rotates the cam 34 to periodically operate the plunger 27 to cause 50 the plunger to force a heel H which has been placed by hand in the position I of Fig. 5 longitudinally of the gripping jaws 14 and 15 to the position II, and feeds the heel past the saw 74.

While a heel is in the position II the drill 84 55 is lowered by the cam 90, lever 91 and link 93 to bore a dowel receiving hole in this heel, and when the next heel is forced along the jaws 14 and 15 by the plunger 27 it will engage the heel that was last drilled and move it to the position III to cause a dowel d to be driven in the 60 hole in the heel. The dowels are supplied by the hopper 105 and are successively presented to the heel by the device 108 in position to be driven by the heel by the pin 101. Means is also provided whereby when a heel is in the position II the heel may be stamped by the dies 58. The cams 63 65 and 90 are driven at the same speed as the cam 34 and 98.

After a heel has been acted upon by the saw 70 74, drill 84, stamping dies 58, and has been strengthened by a dowel d driven in the heel by the pin 101, the heel is ejected at the discharge end of the jaws 14, 15.

I claim:

75 1. In a machine for operating upon heels hav-

ing a shoulder at the front of the heel, in combination, means for tightly but slidably holding the heel in an inverted position while it is operated upon, comprising a support upon which the top surface of the heel rests for sliding movement, a pair of long heel receiving jaws supported in substantially parallel relation to said support to tightly receive the heel between them, one of the jaws being positioned to overlie said shoulder and the other to engage the sloping rear surface of the inverted heel, and means for sliding the firmly gripped heel along said jaws. 10

2. In a machine for operating upon heels having a shoulder at the front of the heel, in combination, means for tightly but slidably holding the heel in an inverted position while it is operated upon by one or more tools, comprising a support upon which the top surface of the heel rests for sliding movement, a pair of long heel receiving jaws supported in substantially parallel relation to said support to tightly receive the heel between them, one of the jaws being positioned to overlie said shoulder and the other to engage the sloping rear surface of the inverted heel, means for sliding the firmly gripped heel along said jaws, and a tool for operating upon the heel held by the jaws. 15

3. In a machine for operating upon wood heels having a shoulder at the front of the heel, in combination means for tightly but slidably holding the heel in an inverted position while it is operated upon in different positions, comprising a support upon which the top surface of the heel rests for sliding movement, a pair of long heel receiving jaws supported in substantially parallel relation to each other and to said support to tightly receive the heel between them, one of the jaws being positioned to overlie said shoulder and the other to engage the sloping rear surface of the inverted heel, means for sliding the firmly gripped heel along said jaws, and tools for operating upon the heel at different points along said jaws. 30

4. In a machine for operating upon heels having a shoulder at the front of the heel, in combination, means for tightly but slidably holding the heel in an inverted position while it is operated upon, comprising a support upon which the top surface of the heel rests for sliding movement, a pair of long heel receiving jaws supported in substantially parallel relation to said support to tightly receive the heel between them, one of the jaws being positioned to overlie said shoulder and the other to engage the sloping rear surface of the inverted heel, and a stamping tool operable through said support to stamp the top face of the heel while it is held by said jaws. 45

5. In a machine for operating upon wood heels, in combination, means for tightly but slidably holding the heel in an inverted position while it is operated upon, comprising a support upon which the top surface of the heel rests for sliding movement, a pair of heel receiving strips supported in substantially parallel relation to each other and to said support to tightly receive the heel between them, one of the strips being positioned to engage the front portion of the heel and the other to engage the sloping rear surface of the inverted heel, means for sliding the firmly gripped heel along said strips, and a tool for operating upon the heel held by the strips. 60

6. In a machine for operating upon heels having a shoulder at the front of the heel, in combination, means for tightly but slidably holding the heel in an inverted position while it is oper- 65

ated upon, comprising a support upon which the top surface of the heel rests for sliding movement, a pair of heel receiving strips supported in substantially parallel relation to each other and to said support to tightly receive the heel between them, one of the strips being positioned to overlie and rest upon said shoulder and the other to engage the sloping rear surface of the inverted heel, tools for operating upon said heel, and means for sliding the firmly gripped heel along said strips to present it to said tools.

7. In a machine for operating upon heels having a shoulder at the front of the heel, in combination, means for tightly but slidably holding the heel in an inverted position while it is operated upon, comprising a support upon which the top surface of the heel rests for sliding movement, a pair of heel receiving strips supported in substantially parallel relation to each other and to said support to tightly receive the heel between them, one of the strips being positioned to overlie and rest upon said shoulder and the other to engage the sloping rear surface of the inverted heel, tools for operating upon said heel, and a power operated plunger for sliding the heel along the strips which firmly grip it.

8. In a machine for operating upon heels having a shoulder at the front of the heel, in combination, means for tightly but slidably holding the heel in an inverted position while it is operated upon, comprising a support upon which the top surface of the heel rests for sliding movement, a pair of heel receiving strips supported in substantially parallel relation to each other and to said support to tightly receive the heel between them, one of the strips being positioned to overlie and rest upon said shoulder and the other to engage the sloping rear surface of the inverted heel, tools arranged at successive points along the path defined by said strips, and means for forcing the firmly gripped heel along said strips to successive positions along said path.

9. In a machine for operating upon heels having a shoulder at the front of the heel, in combination, means for tightly but slidably holding the heel in an inverted position, comprising a support upon which the top surface of the heel rests for sliding movement, a pair of heel receiving strips supported in substantially parallel relation to each other and to said support to tightly receive the heel between them, one of the strips being positioned to overlie said shoulder and the other to engage the sloping rear surface of the inverted heel, a cutter adjacent said strips, and means for moving the firmly gripped heel along said strips to thereby feed the heel against the cutter.

10. In a machine for operating upon heels having a shoulder at the front of the heel, in combination, means for tightly but slidably holding the heel in an inverted position, comprising a support upon which the top surface of the heel rests for sliding movement, a pair of heel receiving strips supported in substantially parallel relation to each other and to said support to tightly receive the heel between them, one of the strips being positioned to overlie said shoulder and the other to engage the sloping rear surface of the inverted heel, and means for resiliently supporting one of said strips in gripping engagement with said heel to firmly hold the heel for sliding movement along the path defined by the strips.

11. In a machine for operating upon heels having a shoulder at the front of the heel, in combination, means for tightly but slidably holding

the heel in an inverted position, comprising a support upon which the top surface of the heel rests for sliding movement, a pair of heel receiving strips supported in substantially parallel relation to each other and to said support to tightly receive the heel between them, one of the strips being positioned to overlie said shoulder and the other to engage the sloping rear surface of the inverted heel, and means for sliding the heel along said support between said strips whereby the heel is introduced between said strips at one end thereof and discharged from the other end of the strips.

12. In a machine for operating upon wood heels having a shoulder at the front of the heel, in combination, means for supporting the heel in an inverted position, comprising a support for supporting the heel with its top surface resting upon the support, a pair of heel receiving jaws mounted on the support in spaced relation thereto to receive the heel between the jaws and support with a sliding gripping action, one jaw being positioned to extend over and engage the heel shoulder and the other jaw being adapted to engage the sloping rear surface of the inverted heel, a drilling tool operable to drill a hole in the heel body through the lift receiving end of the heel, and means for sliding the heel along said support between the jaws to a position in which it is firmly held by the jaws beneath said drill.

13. In a machine for operating upon heels having a shoulder at the front of the heel, in combination, means for tightly but slidably holding the heel in an inverted position, comprising a support upon which the top surface of the heel rests, a pair of substantially parallel strips mounted upon said support to tightly but slidably receive the heel between them, one of the strips being positioned to overlie said shoulder and the other to engage the sloping rear surface of the inverted heel, and means for tiltingly supporting the last mentioned strip for adjustment to cause its heel engaging surface to conform to the slope of the heel.

14. In a machine for operating upon heels having a shoulder at the front of the heel, in combination, means for tightly but slidably holding the heel in an inverted position, comprising a support upon which the top surface of the heel rests, a pair of long heel receiving jaws mounted upon said support in substantially parallel relation to each other to tightly but slidably receive the heel between them, one of the jaws being positioned to overlie and engage said shoulder and the other to engage the sloping rear surface of the inverted heel, and means for pivotally supporting the last mentioned jaw for tilting movement about a longitudinal axis to cause its heel engaging surface to conform to the slope of the heel.

15. In a machine for operating upon heels, in combination, means for tightly but slidably holding the heel in an inverted position, comprising a support upon which the top surface of the heel rests, a pair of substantially parallel strips mounted upon said support to tightly but slidably receive the heel between them, heel drilling means and a dowel driver, means for sliding the firmly gripped heel along said strips to a predetermined position below said drill and adapted to cause the heel which has been drilled to be pushed by the next incoming heel to a second position below the dowel driver.

16. In a machine for operating upon heels, in combination, means for tightly but slidably holding the heel in an inverted position, comprising a support upon which the top surface of the heel rests, a pair of substantially parallel strips mounted upon said support to tightly but slidably receive the heel between them, one of the strips being positioned to engage the front face of the heel and the other to engage the sloping rear surface of the inverted heel, a cutter for cutting off the top lift receiving end of the heel, means for supporting the cutter for angular adjustment relative to the heel, and means for sliding the heel along said support between said strips to present the heel to the cutter.
17. In a machine for operating upon heels, in

combination, means for tightly but slidably holding the heel in an inverted position, comprising a support upon which the top surface of the heel rests, a pair of substantially parallel strips mounted upon said support to tightly but slidably receive the heel between them, one of the strips being positioned to engage the front face of the heel and the other to engage the sloping rear surface of the inverted heel, a cutter for cutting off the top lift receiving end of the heel, means for supporting the cutter for movement axially of the heel and angularly relative thereto, and means for sliding the heel along said strips to present the heel to the cutter.

JAMES S. O'CALLAGHAN.
